UNITED STATES PATENT OFFICE.

ANTONIO TROIANO, OF YONKERS, NEW YORK.

SANITARY APPLIANCE.

1,188,512.

Specification of Letters Patent. Patented June 27, 1916.

Application filed June 10, 1915. Serial No. 33,259.

To all whom it may concern:

Be it known that I, ANTONIO TROIANO, a citizen of the United States, residing in Yonkers, Westchester county, State of New York, have invented certain new and useful Improvements in Sanitary Appliances, of which the following is a specification, reference being had to the drawings forming a part thereof.

10 My invention relates to sanitary devices and particularly to those in use in the ordinary barber shop and hair dressing parlor. Within the past decade a movement to lessen the dangers of contracting contagious diseases and afflictions has grown, aided by State and municipal laws calling for the liberal use of antiseptics and the use of separate articles for each individual. In the barber shop and hair dressing parlor to 20 which my invention is directed, individual shaving cups, brushes and towels have come into such common use that the exception is an extreme rarity. In the treatment of the hair, however, the old fashioned custom of 25 employing the same apron for several customers is still in use. The apron is wrapped around the shoulders and body of the individual with the upper edge thereof tucked in and about the neck of the person. The 30 clippings are thereby prevented from falling down the neck of the wearer or, upon his clothing. It is obvious that that portion of the apron that is folded about the neck of the individual, and in contact therewith 35 will become infected with such diseases as the individual is afflicted, and if wrapped about the neck of a subsequent customer will transmit to him the disease. This danger would be overcome by the employing of individual aprons but in that event the cost of 40 laundering a great number of these during the course of a week would add a considerable item to the cost of operating the establishment.

45 My invention has for its object to provide a collar or neck piece to be folded closely around the neck of the individual that will be so inexpensive that it can be thrown away after use.

50 My invention also has for its object simplicity and economy of manufacture.

My invention has other objects that will appear more fully hereinafter.

55 I shall now describe my invention as illustrated in the accompanying drawings and

will thereafter point out my invention in claims.

Figure 1 is a rear view of one embodiment of my invention shown in use. Figs. 2 and 4 are end sectional views of the same. Fig. 60 3 is an enlarged view of the collar showing the fasteners therein. Fig. 5 is a view of another embodiment of my invention showing another form of fastening device.

The embodiment of my invention illustrated in Figs. 1 to 4 inclusive is shown as comprising a body portion 3 consisting of a soft and downy substance such as cotton, wool or the like mounted on a long band or strip 2, and held therein in a suitable manner. In practice I make use of a rope formed by twisting strands of cotton antiseptically treated which I sew upon a paper band which has also been subjected to an antiseptic treatment. Two fasteners 4 and 5 65 are shown as provided in the strip with their pins pointing in opposite directions. A stiffening piece 7 is provided to give body to the strip and allow for a firm grip of the fasteners thereon.

80 In making use of the embodiment of my invention illustrated the collar is placed about the neck of the individual with one edge 2^b over the edge 2^a in such a way that the pin 4 passes there through and holds 85 it in place. The apron 6 is then folded over the shoulders of the individual and held in place by causing the edge 6^b to be secured by the pin 4 and the edge 6^a by the pin 5. It is thus obvious that the upper edge of the 90 apron does not come in contact with the bare neck of the individual being at all times fastened to the collar below the shoulder formed by the body portion 3. It is also apparent that as the hair is cut and falls from 95 the head of the individual it will be prevented from falling down the neck of the latter by the close contact of the body portion 3 of the collar therewith. The apron 6 is held in place by the pins 4 and 5 of the collar instead of being held by being tucked in and about the bare neck of the individual. When the cutting of the hair is completed 100 the apron 6 is removed and thereafter the collar embodying my invention is thrown away never to be used again.

105 I do not limit myself with respect to the material out of which the body portion 3 is made up nor do I limit myself with respect to the particular form of fasteners 4 and 5, 110

In Fig. 5 I have shown another form of fastening device in which a string 9 anchored to the part 8 on one end of the strip 2 is made to wind around the button 10 on the other end of the strip. The pin 11 is employed to support the apron 6.

It is obvious that various modifications may be made in the constructions shown and described within the spirit and scope of my invention.

I claim:

1. A sanitary neck piece adapted throughout its entire surface to fit closely around the neck of the wearer and comprising a long narrow straight band of flexible material having a strip of softer material mounted along the upper edge thereof, means for fastening together the ends of the band and means mounted on the band for supporting a hair cutting apron.

2. A sanitary neck piece adapted throughout its entire surface to fit closely around the neck of the wearer and comprising a long narrow band of flexible material having a strip of softer material mounted along the upper edge thereof and common fastening means for securing together the ends of the band and a hair cutting apron to said band for the support of said apron.

3. A sanitary neck shield adapted throughout its surface to fit closely around

the neck of the wearer and comprising a long narrow band having a strip of soft material along the upper edge thereof and common means for fastening together the ends of the band and for fastening to said band the upper edge of a hair cutting apron, said means being positioned at a substantial distance from the edges of said band whereby the edge of said apron is shielded by said band from the neck of the wearer.

4. A sanitary neck piece comprising a long flat narrow strip of flexible material adapted to fit throughout its entire length and width about the neck of the wearer and to conform to the curvature and shape of said neck, the ends being arranged to over-lap one another, and a device mounted on the strip near one end thereof and adapted to engage the other end of the strip at any point of their overlapping and thereby secure said ends in their overlapped positions, said device being also adapted to secure a hair cutting apron to said strip for the support of said apron.

In witness whereof I have signed my name in the presence of two witnesses this 2d day of June, 1915.

ANTONIO TROLANO.
